United States Patent [19]

Paull et al.

US00D362432S

[11] Patent Number: Des. 362,432

[45] Date of Patent: ** Sep. 19, 1995

[54] KEYBOARD

- [75] Inventors: **Mike M. Paull; Steven T. Kaneko**, both of Seattle; **Thomas E. Davies, Jr.**, Snohomish, all of Wash.; **Jan Hippen; Penelope C. Yao**, both of Portland, Oreg.
- [73] Assignee: **Microsoft Corporation**, Redmond, Wash.
- [**] Term: **14 Years**
- [21] Appl. No.: **19,133**
- [22] Filed: **Feb. 23, 1994**

Related U.S. Application Data

- [63] Continuation-in-part of Ser. No. 10,111, Jun. 25, 1993, and a continuation-in-part of Ser. No. 10,112, Jun. 25, 1993.
- [52] U.S. Cl. **D14/115**

[57] CLAIM

The ornamental design for a keyboard, as shown and described.

DESCRIPTION

FIG. 1 is a front perspective view of a keyboard showing our new design;

FIG. 2 is a top plan view of the keyboard;

FIG. 3 is a front elevational view of the keyboard;

FIG. 4 is a bottom plan view of the keyboard;

FIG. 5 is a rear elevational view of the keyboard;

FIG. 6 is a left side elevational view of the keyboard; and,

FIG. 7 is a right side elevational view of the keyboard.

UNITED STATES PATENT AND TRADEMARK OFFICE
CERTIFICATE OF CORRECTION

PATENT NO. : Des.362,432
DATED : September 19, 1995
INVENTOR(S) : Paull et al.

It is certified that error appears in the above-identified patent and that said Letters Patent is hereby corrected as shown below:

In the drawings delete figure 4, figure 4 should appear as follows:

Figure 4

Signed and Sealed this
Twenty-sixth Day of March, 1996
